DESIGN FOR A COMBINED COOKING AND HEATING STOVE OR SIMILAR ARTICLE

Cortland W. Davis, Alexandria, Ind.

Application September 9, 1938, Serial No. 79,804

Term of patent 14 years

To all whom it may concern:

Be it known that I, Cortland W. Davis, a citizen of the United States of America, residing at Alexandria, in the county of Madison and State of Indiana, have invented a new, original, and ornamental Design for a Combined Cooking and Heating Stove or Similar Article, of which the following is a specification, reference being had to the accompanying drawing, forming a part thereof.

The figure is a perspective view of a combined cooking and heating stove or similar article, showing my new design. The side of the stove not shown in the drawing is of substantially the same appearance as the side shown in the drawing; and the back of the stove not shown in the drawing is of substantially the same appearance as the front of the stove shown in the drawing, the only difference being that the back is not provided with a door but is continuous excepting for the narrow openings therein corresponding with the narrow openings shown in the front of the stove.

I claim:

The ornamental design for a combined cooking and heating stove or similar article, substantially as shown and described.

CORTLAND W. DAVIS.
